UNITED STATES PATENT OFFICE.

WILLIAM C. HELCHER, OF GALION, OHIO.

COMBINED JAR-CLOSURE AND CAP-EXTRACTOR.

1,149,427.

Specification of Letters Patent. Patented June 8, 1915.

Application filed April 24, 1914. Serial No. 834,199.

To all whom it may concern:

Be it known that I, WILLIAM C. HELCHER, a citizen of the United States, residing at Galion, in the county of Crawford and State 5 of Ohio, have invented certain new and useful Improvements in Combined Jar-Closures and Cap-Extractors, of which the following is a specification.

This invention relates to a combined jar 10 closure and cap extractor particularly adapted for use in connection with milk jars.

The primary object of the invention is to provide a device of this character including 15 a closure which may be used to seal the milk jar after the cap has been removed, and to also provide a cap engaging member which is detachably secured to the closure.

A further object of the invention is to 20 provide a closure carrying a detachable cap engaging member which may be formed of suitable sheet metal and which may be readily attached to or detached from the closure.

25 The invention has as a further object to provide a combined jar closure and cap extractor so constructed that the cap engaging member may be caused to pierce the cap of a jar upon application of the closure to the jar, and upon rotation of the closure may be caused to so engage the cap as to readily effect its removal from the jar upon the removal of the closure. And a still further object of the invention is to generally improve 30 the construction and increase the efficiency of devices of the above described character.

With these and other objects in view my 40 invention will be more fully described, illustrated in the accompanying drawings, and then specifically pointed out in the claims which are attached to and form a part of this application.

In the accompanying drawings: Figure 1 45 is a vertical sectional view showing my improved jar closure and cap extractor applied to the rim of an ordinary milk jar, Fig. 2 is a perspective view of the device, Fig. 3 is a detail perspective view of the cap engaging member, and Fig. 4 is a transverse sectional view taken on the line 4-4 of Fig. 3, and especially showing the disposition of the cutting edges formed on the head of the cap engaging member.

55 Corresponding and like parts are referred

to in the following description and indicated in all the views of the drawings by the same reference characters.

My improved device is especially adapted for use in connection with milk jars and includes a closure for the jar which carries a cap engaging member adapted to effect the removal of the ordinary paper cap as commonly used to close such jars for transportation.

Referring more particularly to the drawings, the numeral 10 indicates the neck of an ordinary milk jar in which is positioned the usual cap or disk 11.

Coming now to the subject of the present 70 invention, my improved device includes a closure 12 which is preferably formed of suitable sheet metal and is provided with a depending peripheral flange 13 adapted to engage over the outer walls of the neck 10 75 to close the jar. Secured to the closure 12 centrally thereof is a handle knob 14. Such knob may be formed of wood or any other suitable material and is centrally bored to receive a bolt 15 which extends through the 80 closure 12 and is connected thereto by a nut 16, screw threaded upon the extremity of the bolt. Mounted upon the inner extremity of the bolt 15 interiorly of the closure 12 is a cap engaging member 17. Such member 85 is preferably formed from a strip of suitable sheet metal and includes the body portion 18 which is provided with an aperture 19 designed to receive the extremity of the bolt 15. The cap engaging member is detachably secured to the closure and may be readily attached thereto or detached therefrom by removing the nut 16. Thus, the cap engaging member may be removed and the closure used independently thereof. 90 However, as the cap engaging member will normally project within the neck of the jar, the presence of said member upon the closure will not be found inconvenient, and the necessity for removing said member from 95 the closure, will therefore not often arise.

The body portion 18 of the cap engaging member is bent at substantially right angles adjacent one extremity as at 20, the portion of the strip so bent extending to provide a substantially triangular or arrow shaped head 21, the strip being transversely notched as at 22 upon either side at the inner extremity of the head 21 to provide a shank 23 and to also provide oppositely disposed 100

shoulders 24 and 25 upon each side of the cap engaging member at the extremities of the shank 23.

The sides 26 of the head 21 converge from the outer extremities of the shoulders 24 toward the free extremity of the head and said sides are reversely beveled to form cutting edges 27.

As shown in Fig. 1 of the drawings, when the closure 12 is applied to the neck 10 of the jar, the cap engaging member will be forced through the disk 11, the cutting edges 27 formed on the head 21 of said member readily piercing the disk. The cap engaging member 17 is so formed that when thus engaged with the disk, the disk will be disposed upon the shank 23 of said member between the oppositely disposed shoulder 24 and 25, the head 12 preferably being forced entirely through the disk. When thus engaged the closure 12 is slightly rotated by the handle 14 upon the neck of the jar causing the shoulders 24 formed at one extremity of the head of the cap engaging member to assume a position slightly out of alinement with the incision made in the disk by the insertion of the head. The shoulders 24 are thus caused to securely engage the disk and as will be readily obvious, the removal of the closure 12 from the jar will also effect the extraction of the disk 11.

In forming the head of the disk engaging member 17, I have sought to provide a construction such as will readily pierce the disk and have accordingly formed the head with a relatively sharp piercing point 28, the side edges of the head being provided with reversely disposed cutting edges 27 which converge toward the piercing point. By this construction a very slight pressure upon the closure 12 will cause the cap engaging member to pierce the disk 11 and danger of forcing the disk inwardly of the neck of the jar or otherwise displacing the disk is reduced to a minimum. It will be further noted that the disk 11 when engaged by the member 17 is held thereon between the shoulders 24 and 25 and thus, in extracting the disk from the jar, the disk will be retained upon the member 17 until manually removed therefrom. It is to be understood that the cap engaging member 17 is preferably formed of suitable non-corrosive metal so that it may not affect the milk contained in the jar. However, par-

ticular attention is called to the fact that if for any reason the cap engaging member 17 should become corroded, or broken, or if for any other reason it should become necessary to remove the member and substitute a new cap engaging member, this desired result may be readily effected. Furthermore, in making the cap engaging member 17 detachable from the closure 12, the manufacture of my improved device has been found to be much simplified, while at the same time a thoroughly efficient construction is provided.

Having thus described my invention what I claim and desire to secure by Letters Patent is:

1. A device of the character described including a closure, a handle carried by the closure, a cap engaging member carried thereby, and a bolt extending through the handle, the closure, and the cap engaging member, said bolt connecting the handle and the cap engaging member to the closure, said cap engaging member being formed from suitable sheet metal and including a body portion bent adjacent one extremity at substantially right angles to form a depending portion terminating in a substantially triangular shaped head arranged upon one side of the vertical axis of the closure and having reversely beveled sides forming cutting edges.

2. A device of the character described including a closure, a handle extending vertically upon one side of the closure, a cap engaging member arranged upon the opposite side of the closure, said cap engaging member being formed from a strip of suitable sheet metal bent intermediate its ends to provide a substantially flat body portion seating against the closure and a vertically arranged head provided with a piercing point and having transversely arranged shoulders formed thereon, and a bolt extending through the handle, the closure and the body portion of the cap engaging member, said bolt detachably connecting the handle and the cap engaging member with the closure.

In testimony whereof I affix my signature in presence of two witnesses.

WILLIAM C. HELCHER. [L. S.]
